(57) **CLAIM**

The ornamental design for a portable cigar stand, as shown and described.

DESCRIPTION

FIG. 1 is a top perspective of a portable cigar stand showing my new design;

FIG. 2 is a bottom perspective view thereof;

FIG. 3 is a front elevation view thereof;

FIG. 4 is a right elevation view thereof;

FIG. 5 is a rear elevation view thereof;

FIG. 6 is a left elevation view thereof;

FIG. 7 is a top plan view thereof; and,

FIG. 8 is a bottom plan view thereof.

In the drawings, the evenly-spaced broken lines depict portions of the portable cigar stand that form no part of the claimed design. Additionally, the dash-dot-dash broken lines depict the boundaries of the claimed design. The appearance of any portions of the portable cigar stand between the symbolic break lines shown in FIGS. 1-6 form no part of the claimed design.
